Fig. 1.

Fig. 2.

Fig. 3.

To all whom it may concern:

Be it known that I, Nat Cordis, a citizen of the United States, residing at Silver Lake, in the county of Kenosha and the State of Wisconsin, have invented a new, original, and ornamental Design for Vending Machine for Newspapers and Similar Article, of which the following is a specification, reference being had to the accompanying drawing, forming a part hereof and wherein:

Figure 1 is a top plan view of a vending machine for newspapers and similar article, showing my new design;

The side of the vending machine not shown is substantially plain in appearance.

I claim:

The ornamental design for a vending machine for newspapers and similar article, as shown and described.
